UNITED STATES PATENT OFFICE.

DOLPHUS TORREY, OF NEW YORK, N. Y.

CAR-BRAKE.

SPECIFICATION forming part of Letters Patent No. 276,938, dated May 1, 1883.

Application filed January 12, 1883. (No model.)

To all whom it may concern:

Be it known that I, DOLPHUS TORREY, a citizen of the United States, residing at New York, in the county and State of New York, have invented a new and useful Improvement 5 in Car-Brakes, of which the following is a specification.

My invention relates to a brake mechanism in which the force to operate the brakes is derived 10 from the axle rotation while the brakes are applied, and is stored in an accumulator-spring, and is sufficient to charge at the proper time a working-spring, which working-spring, when released, effects the succeeding application 15 of the brakes.

For clearness of explanation I apply the term "actuating mechanism" to a mechanism which sets in operation or permits, initiates, or compels 20 the action of another mechanism by which the braking force is applied to the wheels, and the term "operating mechanism" to that which exerts or communicates the braking force.

The train of mechanism includes preferably a friction-windlass brake of any approved 25 construction, a spring for setting the friction apparatus against the axle, or a wheel or pulley thereon, which spring is held charged with energy for its expansion until released by tripping a catch controlled by an electro-magnet 30 or other means, and another spring which, as a receiver and accumulator, is charged with energy by the rotation of the friction-windlass. The accumulator-spring is held restrained by a catch while the brakes are applied. When 35 the brakes are released the release of the accumulator-spring takes place automatically and it expands, drawing into confinement, by means of a suitable connection and catch, the working-spring, which is then automatically, 40 released from the accumulator-spring, which served for putting it under strain, and is held by a tripping-catch ready for service whenever the electric circuit is broken or other adopted device for tripping the catch is operated.

In the line of chain or rod connecting the receiving-spring with the source of energy for operating the apparatus is placed a device 45 called a "releasing-clutch," the preferable form of which includes a shaft having a crank at one end, upon which shaft is fastened a ratch-

et-wheel. Over this ratchet-wheel is a loose pulley, which carries one or more pawls for engaging with the ratchet-teeth, and a spring fastened one to the pulley and the other to a 55 hanger or pillow-block. The chain from the motor is wound upon this pulley, and may be attached to the pulley-face or to an arm extending out from it. The chain from the receiving-spring is attached to the end of the 60 crank upon the shaft. The purpose of this releasing mechanism is to permit the recoil of the receiving-spring while the chain extending to the motor is under stress. The dimensions and proportions of the pulley and crank 65 are such that the greatest movement of the motor-chain effects less than a full revolution of the shaft and crank, while a half-revolution of the crank draws the receiving-spring into 70 position to be held confined by its catch. The crank is set so that the movement of the motor begins with the crank at its center nearest the spring. The pull of the motor-chain carries the crank past its farthest center in position to be rotated forward by the pull of the receiving-spring without communicating any stress 75 to the motor-chain, owing to the escape of the ratchet-wheel by its pawl. The purpose of the arm extended out from the pulley is to enlarge the sweep of the motor-chain and prevent its 80 rotating the crank past its inner center.

The apparatus herein described is represented as being actuated by a magnetic current, with devices by means of which, while the magnetic current is on, the brakes are off, 85 and when the magnetic current is broken the brakes are applied. By this arrangement there is secured an automatic application of the brakes should the train break in two and sever the connecting-wire. The source of the mag- 90 netic current is a matter of indifference, so far as the working of this invention is concerned.

It is contemplated that the tripping or actuating mechanism may be worked by the use of a train-cord, as shown in my application for 95 Letters Patent, dated October 14, 1882, No. 74,269, or by the use of lines connecting the working-spring and the tripping device from car to car, as shown in my application for Letters Patent, dated October 23, 1882, No. 74,981. 100 The springs may take the form of lever-arms, to which the connections with the actuating

and operating mechanism are respectively attached; or hinged arms may be employed, acted upon by springs of coiled or other form. The springs and their attached catches, trips, and associated devices may be located either upon the truck or the car-body, as may be desirable. The springs may be in the form of spirals, or of elliptical or other shape, as may be found most desirable in particular cases.

10 In the accompanying drawings, Figure 1 is a plan view of so much of the apparatus as is necessary to illustrate the invention, the parts being shown in the positions they occupy during the ordinary running of the cars before the brakes are applied. Fig. 2 is a transverse section on the line 2 2, Fig. 1, of the receiving and working spring-levers, showing the connecting grapple between said spring-levers and the tripping device thereof in elevation. 15 Fig. 3 is a transverse section through the car-axle on the line 3 3, Fig. 1, showing the friction devices in elevation. Fig. 4 is a plan of the catch or detent on a larger scale. Fig. 5 is a plan of the keeper of the same, also on a larger scale. Fig. 6 is an elevation of the lever or spring connection on a larger scale. Fig. 7 is a plan of the apparatus, showing the working parts in the position which they assume on the first application of the brakes. 25 Fig. 8 is a plan of the same, showing the receiving spring-lever under strain in readiness for applying strain to the working spring-lever when released. Fig. 9 is a perspective view of the mechanism, showing a modification in the friction-windlass, as hereinafter described. Fig. 10 is a vertical longitudinal section of a car-truck, showing the operating mechanism in elevation. Fig. 11 is an elevation, looking endwise of the car; and Fig. 12, a plan of connections employed for communicating stress to the accumulator-spring from a limited vertical movement which is imparted to the brake-beams in one or the other direction on the first application of the brakes. 35 Fig. 13 is a plan of the spring-levers, showing a modification in the construction of the shackle. 40 45

In Figs. 1, 2, 7, and 8 I have shown the receiving and working springs formed of a single bar, and constituting lever-arms connected together at their fulcrum-points. Jointed inflexible levers with a spring or springs separate from said levers to press them apart may, if preferred, be employed, as shown in Fig. 9 or 13; or springs of other forms may be used.

In Fig. 1, 1 represents the receiving-spring, and 2 the working-spring, connected together through the medium of elastic coils 3 3, and forming the arms of a U-shaped bar fastened by a strap, 4, to a beam, B, of the car or truck frame, so as to leave the ends of the arms 1 2 free to be drawn together and to spring apart when released.

5 represents a grapple or connecting-bar hinged on the receiving-spring 1 at 6, and formed at its extremity with a hook, 7, to catch the working-spring 2 when the springs

are drawn together. The receiving-spring 1 is of greater strength than the working-spring 2, so that when the springs are connected by 70 the grapple and the receiving-spring 1 is not otherwise constrained, the said receiving-spring will recede to its normal position shown in Fig. 1 and draw the working-spring 2 into the constrained position shown in the 75 same figure.

Chaius 8^a, attached to the respective members of a releasing-clutch, 88, and one of them passing over a pulley, 9, connect the accumulator or receiving spring 1 with a wrist, 10, on a crank-wheel, 11, mounted on the extremity of a shaft, 12, which has its bearings in hangers 13, swinging from the body of the car, and having also keyed upon it friction-wheels 15, which are drawn in contact with a sleeve, 16, on the axle A, to impart rotation to said wheel for the purpose of applying the brakes. 8c 85

18 represents a brake-chain, which in practice is connected through a customary equalizing-lever, 18^a, Fig. 9, with the first lever of an ordinary brake system. 90

For drawing the friction-wheels 15 into contact with the friction-sleeve 16, the shaft 12 is connected by a yoke, 19, and a rod or chain, 20, with the working-spring 2. For the purpose of holding the springs or levers 1 2 in the constrained positions to which they are drawn, the first by the rotation of the shaft 12 and crank 11 10, and the second by the retraction of the first when released, suitable catches are provided, which may be made in one, as shown in Fig. 1, where the said catches take the form of a T-shaped bar, 21, fulcrumed at 22 on the beam B, and having at the extremities of its head oblique teeth 23 24, the first of which catches the extremity of the receiving-lever 1 and the other the extremity of the working-lever 2 when they are respectively drawn in under constraint. The stem of the T-shaped catch 21 is held in central position by springs 25, confined between flanges 26 on a keeper, 27, which is pivoted on the same fulcrum-pin, 22, as the catch 21, so that the keeper and catch together may move freely on the fulcrum 105 110

22; but if the keeper be held the catch 21 may have an independent movement relatively thereto, resisted by the springs 25. The keeper 27 is held in its central or normal position by a latch 28, pivoted at 29 to the beam B, and formed with opposite oblique shoulders 30 31, which engage alternately with corresponding lugs, 30^a 31^a; Fig. 5, on the keeper 27, so as to resist the movement of the keeper in one or the other direction when the latch 28 is held at either extremity of its movement by the respective teeth 32 33 of a pawl, 34, which is pivoted at 35, and in this illustration constitutes the armature of an electro-magnet, 36, and when released by said magnet is thrown back by a spring, 37, so that when the electro-magnet is charged the latch 28 will be held in the position shown in Fig. 1, confining the working-spring 2 under strain, and when the magnet is inert by the breaking of the circuit

the latch 28 will be held in the position shown in Fig. 7, in readiness to confine the receiving-lever 1 under strain. The inclined backs of the teeth 23 24 permit the ends of the springs to pass within the catch, the force exerted through the medium of such inclined backs being sufficient to overcome the resistance of the springs 25; but the springs 25 effectually resist the outward pressure of the spring-lever 1 2 against the abrupt faces of the teeth 23 24, so that such outward pressure cannot move the catch 21 within its keeper, but will move the catch and keeper bodily on their common pivot, 22, throwing out the latch 28 by the pressure of the lug 30^a or 31^a on the oblique shoulder 30 or 31 when the said latch is released by the movement of the pawl 34 in one or the other direction under the action of the electro-magnet 36 or spring 37.

38, Fig. 2, represents a projection on the beam B to trip the grapple 5, and thus release the working-spring 2 from the receiving-spring 1 when said working-spring is drawn into engagement with the catch 21.

25 In order to permit the release of the accumulator-spring, as hereinafter explained, while the motor-connections 11 10 8 are under strain, a release-clutch, 88, is introduced into the chain-connection 8 8^a. This device I have described in detail and claimed in another application of even date herewith.

The parts being in position shown in Fig. 1, as in the ordinary running of the car, if the electric circuit through the train be broken for the purpose of applying the brakes, or by the accidental uncoupling of the cars, the electro-magnet 36 releases the pawl 34, permitting the spring 37 to throw the tooth 32 out of engagement with the latch 28. The outward pressure of the working-lever 2, acting through the catch 21, keeper 27, and lug 30^a against the oblique shoulder 30 of the latch 28, will throw out the said latch and escape from the catch 21, drawing the friction-shaft 12, with its wheels 15, in contact with the friction-sleeve 16 on the axle A. This position of the parts is shown in Fig. 7. The friction-shaft 12 is thus rotated, and by reason of the attachment of the brake-chain 18 at a considerable radial distance from the center of the shaft the slack of the brake-chain is instantly taken up, and the said chain is then wound on the shaft 12 with the necessary force to apply the brakes. At the same time the receiving-spring 1 is strained by the rotation of the friction-shaft through the connections 11 10 8 8^a, and is caught by the tooth 23 of the catch 21, the spring 25 on the opposite side yielding to the pressure of the end of the spring-lever 1 against the inclined back of said tooth 23. The extremities of the spring-levers are provided, as shown, with anti-friction wheels to permit them to pass more easily into engagement with the teeth 23 24. This movement of the spring-lever 1 causes the grapple 5 to engage with the lever 2. This position of the parts is shown in Fig. 8. When the brakes are to be released the electric cur-

rent is again closed, causing the magnet 36 to draw the pawl 34, so as to release the latch 28 from the tooth 33. The resilience of the spring 70 lever 1, acting through the tooth 23, keeper 27, and lug 31^a, will now throw the latch 28 into the position shown in Fig. 1, permitting the spring-lever 1 to escape from the catch 21 and draw the working-lever 2 into engagement 75 therewith, where it is held by the tooth 24, lug 30^a, shoulder 30, latch 28, and the tooth 32 of the pawl 34, the grapple 5 being at the same time lifted from the spring 2 by the projection 38, so that said spring may instantly apply the brakes when the current is again broken. The receiving-spring 1, in recoiling, pulls the working-spring 2 into its strained position, in taking which it passes and is held by the catch 21. After the working-spring passes 80 its catch, the grapple from the receiving-spring is automatically released by contact with the projection 38. While the brakes are off, the receiving-spring lies expanded and the working-spring compressed, the latter being held 85 by a catch. While the brakes are on, the working-spring is expanded and the receiving-spring compressed. The tripping devices for both springs are preferably combined in a single device which has movements controlling 90 the springs alternately. This tripping device is preferably composed of two parts, only one of which moves in catching the springs, while both move in releasing them. The first includes an arm confined by two counter pressing springs and two arms which form the detents. The second includes the fulcrums for the springs which contain the catch and keeper. This keeper is engaged with a latch which prevents it from swinging in one or the other 95 direction. The points of contact between the latch and keeper are sloped in excess of the angle of friction, so that unless the latch is held in position the keeper will be swung by the stress of the receiving or working spring 100 against its confining-catch. One end of the latch is pivoted, and the other held by a vibrating lever which is controlled by the armature of an electro-magnet and spring. While the magnet is charged by a current of electricity the 105 vibrating lever locks the latch in and prevents the release of the working-spring 2, but permits the escape of the receiving or accumulator spring 1. When the magnetic current is off, the vibrating lever locks the latch out and prevents the release of the receiving-spring, but permits the escape of the working-spring.

The modification in the friction-windlass shown in Fig. 9 consists in supporting the windlass 15 from a pivoted lever, 13^a, which is operated by a connection, 20, from the working-spring 2, attached at 45 to its upper end, instead of being attached to the windlass-shaft, as before shown. This figure also illustrates mechanical adaptations necessitated by placing the apparatus on the car body instead of on the spring-plank of the truck. A is the axle, upon which is mounted the drum 16. 42 is the flange of the drum on the axle. 15 is the fric-

tion-wheel, which, when forced into contact with the rotating drum 16, turns the shaft 12 for winding up the brake-chain 18. The pivot 43 of the hangers 13^a is supported by the braces 44, attached to the truck-timbers. The brake-chain is attached at 46 to the friction-wheel 15 eccentrically, so that the first part of the rotation of the windlass will effect a quick take-up of the brake-shoes. In Fig. 9, 1 represents the accumulator or receiving lever, and 1^a its spring. 2 represents the working-lever, and 2^a its spring.

In utilizing stress communicated from the vertical movement of the brake-beams to charge the accumulator or receiving spring, the brake-beams are hung so that they rise or fall with the face of the wheels when the brakes are applied. Their hangers are attached to crank-arms, which cranks are mounted upon shafts that pass through the truck-timbers. The cranks at the opposite ends of the shafts are opposed, so that the beams are balanced against each other, and so that their motions of rising and falling with the wheels are co-operative in turning the shaft. The crank upon one end of each shaft is T-shaped, the head of the T being set in a perpendicular position. From the opposite arms of the T, connecting lines of rods or chains extend to the end of a lever which is pivoted near the center of the truck-timber. The devices so arranged cause the stress of the moving brake-beam to pull upon the pivoted lever in whichever way the brake-beams move, the two beams pulling in unison and combining their stresses upon the one lever, which always moves in the one direction without regard to the direction either brake-beam may move. From this combining-lever an arm extends at right angles, from which a connection extends to the receiving-spring of the brake apparatus.

To prevent an application of the brakes when a car is detached from a train, or at other times, when desired, provision is made by means of a hand-lever, 50, placed upon the top of the car, or wherever it may be convenient, to which is attached eccentrically a chain connection, 51, extended to the dog 52, which is controlled, when idle, by the spring 53. By turning the handle 50 the dog 52 presses the latch 34 against the magnet 36 and prevents the release of the working-lever when the magnet is not charged.

With the method of utilizing the brake-beams to operate the apparatus the devices will necessarily be modified according to whether the beams are hung inside or outside of the wheels. In the former case the arrangement may be substantially as shown in the Figs. 11 and 12. Two shafts, 63 63^a, are set crosswise the truck-bolster and projecting beyond its faces, so that cranks 62 64 can be attached to their ends. The brake-beam hangers 61 are attached to the horizontal arms of these cranks, which crank-arms are made to rise and fall by the thrust or pull of the hangers whenever the

brakes are applied. Upon one end of each shaft 63, and at opposite sides of the truck-timbers, the crank supporting the beam-hanger is made of a T shape, and set with the head 65 in an upright position. From the T-heads 65 of the cranks, chains 66 extend to the bell-crank lever 67. 68 is an arm of the lever 67, to which is attached the motor-chain 8, that transmits stress to the apparatus. When the brakes are applied the beams rise or fall with the direction of wheel rotation, and their hangers 61 communicate a stress, through the cranks 62 64 65, the chain 66, the lever 67 68, and chain 8, to the accumulator-spring 1, due to the coefficient of friction between the wheels and brake-shoes. By having the amount of vertical movement made by the beams in rising or falling as many times greater than is the movement of the beams in approaching the wheels as the coefficient of friction is contained in unity, we gain the power which, stored in the receiving or accumulator spring, may be subsequently used to again apply the brakes. Of course there must be a margin to cover the loss of energy by friction of the parts.

A modified construction of grappling device is shown in Figs. 9 and 13. The grapple 70 is fastened to one of the levers. It has attached to it a spring, 71, which presses against the pin 74 and forces the grapple against the pin 73. As the receiving-lever 1 draws the working-lever 2 into constraint it pulls the notch 75 against the stop 76 and forces the grapple free from the pin 73, so that the hook 72 will not hold the working-lever should it be freed. This freeing of the pin 73 from the hook 72 takes place after the working-lever is within the catch 21. The brakes being on and the receiving-lever drawn into constraint, it pushes the grapple 70 through between the pins 73 and 74, and the spring 71 insures the engagement of the hook 72 with pin 73, so that with the subsequent release of the receiving-lever the working-lever is drawn into constraint and the grapple automatically freed.

Having thus described my invention, the following is what I claim as new therein and desire to secure by Letters Patent:

1. A brake-actuating apparatus having two springs, one serving as an accumulator to receive and store power derived from the rotation of the wheels, and the other receiving power from the first when this is released, and holding such power to apply the brakes when it is itself released.

2. The combination of a pair of spring-levers, a connection with the wheel or axle applying a strain to one of said levers by the rotation of the wheels, and a connection between the levers applying a strain to the second by the reverse movement of the first lever when released.

3. A pair of levers moved in opposite directions by springs, catching and tripping devices acting alternately on said levers to lock and release the same, a connection putting the

spring of the first lever under strain by the rotation of the wheels, a connection between the levers putting the spring of the second lever under strain by the reverse movement of the first when released, and a connection from the second lever applying the brakes by the reverse movement thereof when released.

5 4. In combination with a pair of levers or springs, a pivoted catch the opposite arms of which alternately receive and hold the levers or springs, and a pivoted keeper which determines by its engagements the retention or release of the respective levers or springs.

10 5. The combination of a pair of levers or springs, a pivoted keeper having two teeth facing in opposite directions, said teeth having inclined faces which engage with a latch, and a latch having notches set in reverse relation to the keeper for controlling the movement of the same.

15 6. The combination of a pair of levers or

springs, a vibrating catch or keeper for alternately locking or holding the same under strain, and a vibrating latch to retain the catch or keeper against the pressure of the levers in opposite direction.

7. The combination, with a pair of levers or springs, of a latch controlling the movements of a catch or keeper which itself determines the retention or release of the levers or springs, and an electro-magnet controlling said catch or keeper.

10 8. An automatic car-brake having the corresponding ends of two brake-beams connected to opposite ends of rotating shafts mounted in the car-timbers longitudinally to the car, substantially as described.

DOLPHUS TORREY.
